(57) **CLAIM**

The ornamental design for a spur, as shown and described.

DESCRIPTION

FIG. 1 is a perspective view of a spur according to my new design. The drawing of a heel of a boot in dotted line is provided to illustrate an environment in which the spur may be used and forms no part of the claimed design.

FIG. 2 is a top plan view of the spur shown in FIG. 1. A bottom plan view of the spur is identical to the top plan view. FIG. 3 is a left elevational view of the spur shown in FIG. 1. A right elevational view of the spur is identical to the left elevational view; and,

FIG. 4 is a rear elevational view of the spur shown in FIG. 1.
